UNITED STATES PATENT OFFICE.

JOHN J. HESSE AND LUCIAN STANEK, OF BOSTON, MASSACHUSETTS, ASSIGNEES TO
HESSE MOTION PICTURE MACHINE COMPANY, A CORPORATION OF MASSACHU-
SETTS.

DRIVING MECHANISM.

1,162,922.

Specification of Letters Patent.

Patented Dec. 7, 1915.

Application filed October 29, 1914. Serial No. 869,330.

To all whom it may concern:

Be it known that we, JOHN J. HESSE and LUCIAN STANEK, citizens of the United States, residing at Boston, in the county of 5 Suffolk and State of Massachusetts, have invented new and useful Improvements in Driving Mechanism, of which the following is a specification.

This invention relates to apparatus for 10 feeding motion picture films and has for its object to provide a simple, positive and accurate means adapted to rapidly advance the film consisting of a series of pictures and intermittently present successive pictures in said series to the projecting instrumentalities connected with the apparatus.

The object of the invention is further to 15 provide means for maintaining the pictures on said film stationary in front of said projecting instrumentalities and for a predetermined period.

Another object of the invention is to provide means for adjusting said locking means whereby any looseness or play, due to the 20 wearing of the several parts of the device, may be removed.

The invention consists in the combination 25 and arrangement of parts set forth in the following specification and particularly 30 pointed out in the claims.

Referring to the drawings: Figure 1 is a vertical section, partly in elevation, taken through a device embodying our invention, certain unimportant details of said device 35 being broken away to save space in the drawings. Fig. 2 is a side elevation of the device illustrated in Fig. 1 looking toward the right in said figure. Fig. 3 is a section taken on the line 3—3 of Fig. 1.

Like numerals refer to like parts throughout the several views of the drawings.

In the drawings, 5 represents a frame upon which are supported the several elements of the device embodying our invention. Upon the frame 5 is a shaft 6 journaled to rotate in bearings 7—7, said shaft having secured thereon a sprocket 8 constructed to engage the perforations in the film and advance the pictures constituting 45 said film into the range of the projected rays of light. The shaft 6 constitutes the driven member of a pair of shafts mounted in said frame 5. A shaft 9 is preferably arranged below the shaft 6 and preferably 50 parallel therewith and constitutes the other

one of the pair of shafts and the driving shaft of said pair, said driving shaft receiving a continuous rotary motion from any desired source not shown in the drawings.

An intermittent rotary motion is im- 60 parted to the shaft 6 from the shaft 9 by means preferably consisting of a disk 10 having a hub 11 arranged to receive one end of the shaft 6. A series of laterally disposed projections or pins 12 are arranged upon 65 one face of the disk 10. A bifurcated member or actuator 13 is secured to the end of the shaft 9 adjacent the disk 10, said actuator 13 having a projection or tooth 14 at one side thereof within the end of which is 70 a notch or recess 15 suitable to receive one of the pins 12. As the shaft 9 is rotated the actuator 13 is also rotated, by reason of its being secured thereto, and causes the side of said projection 14 to engage one of 75 the pins 12 and the recess 15 to receive the next pin in the series to that engaged by the side of said projection, thus advancing the disk the distance equal to that of two pins and as there are preferably 8 pins the 80 disk 10 will be rotated one-quarter of a turn, which distance is sufficient to advance one film to the projecting instrumentalities of the apparatus. It will be evident that but a small portion of each rotation of the shaft 85 9, or at least the actuator 13 secured to said shaft, will be required to operate the disk 10 and as said projection 14 escapes from the last pin engaged thereby, said disk 10, so far as the actuator 13 is concerned, will be 90 free to rotate.

It is essential in this particular type of apparatus that the driven member be prevented from rotating between the successive intermittent rotary movements thereof, and 95 locking means have been provided for accomplishing this result which preferably consists of a rotary member or ball 16 arranged in a suitable recess 17 formed in a detachable portion 25 of the frame 5, preferably beneath the driven member or shaft 6. Said ball is permitted to move substantially along a plane extending from the axis of the shaft 6 to the axis of the shaft 9. A groove 18 is formed about the periphery of 100 the shaft or driven member 6, preferably in the outer surface of the hub 11 within which groove said ball is adapted to rotate. A plurality of recesses 19 are arranged about said driven member along the groove 105 110

18, said recesses being capable of receiving a portion of the ball 16 to an extent sufficient to retard or check the rotary movements of the disk 10 and its shaft. At the proper time the ball 16 is elevated, by suitable means, into the recesses 19, this movement being best accomplished by means of a second ball 20 arranged in a recess 21 similar to the recess 17 and in alignment with said last named recess, said ball having a rotatable engagement with the driving member 9, preferably through the instrumentalities of a collar 22 which constitutes the hub for the actuator 13. A groove 23 is also provided in the periphery of the collar 22 and in this groove the ball 20 has its contact with said collar. The groove 23 has a depressed portion 24 extending circumferentially thereof and constituting a cam, a distance sufficient to permit the ball 20 to be depressed during the time the actuator 13 is engaging the pins 12, preferably one-quarter of a rotation of said actuator. As the ball 20 is moved radially relatively to the axis of the shaft 9, the ball 16 being operatively connected therewith would likewise be moved radially relatively to the member 6 and the depression 24 in the groove 23 is timed so that said radial movement of the ball 16 will take place when the recesses 19 are alining with the recess 17. Means are also provided for adjusting the balls 16 and 20 toward and away from each other, thus to eliminate any looseness or play produced by the wearing away of the balls and their coöperating members. To accomplish this result a wedge-shaped separator 26 is interposed between the balls 16 and 17 and arranged to be moved substantially at right angles to the plane passing through the axes of the members 6 and 9, said member 26 being pivotally secured at 27 to a slide 28 arranged to reciprocate in the portion 25 of said frame. The pivot 27 of said member permits said separator to move with the balls when the same are actuated to lock the member 6 against rotation. To adjust the slide 28 a nut 29 is rotatably arranged in a portion of the frame 5 and has screw-threaded engagement with a threaded stem 30, forming a part of the slide 28, and by the rotation of the nut 29, said slide will be rotated to force the separator 26 between the balls or withdraw the same therefrom.

The general operation of the apparatus hereinbefore specifically described is as follows: A continuous rotary motion is imparted to the shaft 9, which motion is transmitted intermittently through the actuator 13 and disk 10 to the driven member or shaft 6 upon which the film sprocket 8 is fast, thus moving the film to successively present the pictures thereon to the projecting apparatus. As the shaft 9 is rotated the ele-

vated and depressed portions of the groove 23 are alternately presented to the ball 20, thus causing said ball to be moved radially relatively to the shaft 9, likewise causing the ball 16, through the separator 26, to be moved radially relatively to the shaft 6 and at the proper time to enter and be withdrawn from the recesses 19 and thereby alternately lock and unlock said member at the proper times in its operation. 75

By means of a sensitive adjusting means for the separator 26 it will be obvious that all excessive movements of the balls or driven or driving members relatively to each other may be quickly and easily removed and the coöperating parts always maintained at the highest point of efficiency, while at the same time the driven and driving members will be retained in their proper alinement by means of the balls 16 and 20 and their coöperating grooves, which prevent the slightest longitudinal movement of either of said members relatively to the other. 80 85

Having thus described our invention what we claim and desire by Letters Patent to secure is: 90

1. An apparatus of the class described having, in combination, a driven member provided with a recess in its periphery, means for imparting an intermittent movement to said driven member, a ball adapted to enter said recess and lock said driven member against rotation, and means adapted to successively move said ball into said recesses and permit the same to withdraw therefrom. 95 100

2. An apparatus of the class described having, in combination, a driven member provided with a peripheral recess, a driving member adapted to impart an intermittent movement to said driven member, a ball adapted to enter said recess and lock said driven member against rotation, and a cam on said driving member adapted to move said ball into said recess. 105 110

3. A device of the class described having, in combination, a driven member, a driving member arranged to impart an intermittent rotary motion to said driven member, a groove formed in the periphery of said driven member, a locking member adapted to engage said driven member within said groove to prevent a longitudinal movement of said driven member relatively to said driving member, said groove being interrupted by a plurality of recesses adapted to receive a portion of said locking member, and means adapted to move said locking member into said recesses. 115 120

4. An apparatus of the class described having, in combination, a driven member, a driving member arranged to impart an intermittent rotary motion to said driven member, a ball engaging the periphery of each of said members, said driven member 125 130

- having a recess in its periphery adapted to receive a portion of the ball engaging said periphery, means adjustably arranged between and in engagement with the balls 5 engaging said peripheries, said means adapted to separate said balls, and means on said driving member adapted to actuate said balls to lock said driven member against rotation.
- 10 5. A device of the class described having, in combination, a driven member, a driving member adapted to impart an intermittent rotary motion to said driven member, said driven member having a groove arranged 15 about the periphery thereof, a ball arranged to engage said driven member within said groove, said driven member also having a plurality of recesses arranged at given points along said groove adapted to receive 20 portions of said ball, and means actuated by said driving member adapted to cause said ball to successively enter said recesses and prevent movement of said driven member while in said recesses.
- 25 6. A device of the class described having, in combination, a driven member, a driving member arranged to impart an intermittent rotary motion to said driven member, said driven member having a plurality of recesses formed about its periphery, a rotary locking member arranged intermediate of the peripheries of said driven member and said driving member and adapted to be moved to successively enter the recesses in 30 said driven member and while therein to lock said member against rotation, and means formed upon the periphery of said driving member adapted to move said rotary locking member.
- 35 7. A device of the class described having, in combination, a driven member, a series of pins on said driven member, a rotatable bifurcated actuator arranged to engage said pins and intermittently rotate said driven 40 member, and means adapted to lock said driven member against rotation between the movements imparted thereto by said actuator.
- 45 8. A device of the class described having, in combination, a driven member, a driving member arranged to impart an intermittent rotary motion to said driven member, said driven member being provided with an annular groove extending about its periphery, said driven member having a plurality of recesses arranged along said groove, said driving member also having an annular groove in its periphery, a portion of said groove being depressed, a ball adapted to 50 engage said driven member within its groove, and a second ball adapted to engage said driving member within its groove, said balls adapted to be actuated during the presentation of the groove and depressed portion of the groove in said driving member
- thereto to successively enter and be removed from the recesses in said driven member, whereby said driven member may be prevented from rotating between the successive intermittent rotary movements thereof. 70
9. An apparatus of the class described having, in combination, a pair of parallelly disposed rotary members, means arranged to impart an intermittent rotary motion to one of said members from the other of said members, a disk secured to the driven member of said pair of parallelly disposed members, a series of laterally disposed projections on said disk, a bifurcated actuator secured to the driving member of said pair of parallelly disposed members, said actuator adapted to coöperate with said projections and rotate said disk a portion of a rotation, said disk having a groove formed therein, a ball disposed intermediate said parallelly 80 disposed members and movable along a plane containing the axes of said members, said ball adapted to rotate in said groove, said disk also having a plurality of recesses arranged along said groove, and means adapted to move said ball during the rotation of said driven member successively into said recesses to prevent the rotation of said driven member between the successive intermittent movements thereof. 85
10. A device of the class described having, in combination, a driven member provided with a groove extending about its periphery, said driven member also having a plurality of recesses disposed along said groove, a driving member arranged to impart an intermittent rotary motion to said driven member, said driving member also having a groove extending about its periphery and a depression extending along a predetermined portion of said groove, a pair of balls interposed between said driven and driving members and adapted to engage said grooves and to be moved by the alternate presentation of the elevated and depressed portions of the 100 groove in said driving member successively into and out of the recesses in said driven member, and means for adjusting said balls toward and away from each other. 105
11. A device of the class described having, in combination, a driven member provided with a groove extending about its periphery, said driven member also having a plurality of recesses disposed along said groove, a driving member arranged to impart an intermittent rotary motion to said driven member, said driving member also having a groove extending about its periphery and a depression extending along a predetermined portion of said groove, a pair of balls interposed between said driven and driving members and adapted to engage said groove and to be moved by the alternate presentation of the elevated and depressed portions of the 115 groove in said driving member successively 120
12. A device of the class described having, in combination, a driven member provided with a groove extending about its periphery, said driven member also having a plurality of recesses disposed along said groove, a driving member arranged to impart an intermittent rotary motion to said driven member, said driving member also having a groove extending about its periphery and a depression extending along a predetermined portion of said groove, a pair of balls interposed between said driven and driving members and adapted to engage said groove and to be moved by the alternate presentation of the elevated and depressed portions of the 125 groove in said driving member successively 130

into and out of the recesses in said driven member, and a wedge adapted to be moved between said balls and move said balls away from each other.

5 12. An apparatus of the class described having, in combination, a driven member, a driving member adapted to impart an intermittent rotary motion to said driven member, said driven member having a groove extending about its periphery, said driven member also having a plurality of recesses arranged along said groove, said driving member also having a groove extending about its periphery, a portion of said groove 10 being depressed, a pair of rotary members arranged beneath said driven member intermediate said driven member and said driving member and adapted to move substantially along a plane containing the axes of 15 said driving and driven members, one of said rotary members adapted to rotate in the groove in said driven member, the other of said rotary members adapted to rotate in the groove in said driving member, the 20 rotary member engaging said driven member adapted to be moved into and out of the recesses in said member by the alternate presentation of the elevated and depressed portion of the groove in said driving member to its rotary member, a separator interposed between said rotary members adapted to be moved transversely of said plane to move said rotary members into their respective grooves, and means adapted to adjust 25 said separator:

30 13. An apparatus of the class described having, in combination, a driven member, a driving member adapted to impart an inter-

mittent rotary motion to said driven member, said driven member having a groove extending about its periphery, said driven member also having a plurality of recesses arranged along said groove, said driving member also having a groove extending about its periphery, a portion of said groove 40 being depressed, a pair of rotary members arranged beneath said driven member intermediate said driven member and said driving member and adapted to move substantially along a plane containing the axes of 45 said driving and driven members, one of said rotary members adapted to rotate in the groove in said driven member, the other of said rotary members adapted to rotate in the groove in said driving member, the rotary member engaging said driven member adapted to be moved into and out of the recesses in said member by the alternate presentation of the elevated and depressed portion of the groove in said driving member 50 to its rotary member, a slide arranged to move substantially at right angles to said plane, a wedge-shaped separator pivotally secured to said slide and interposed between said rotary members and adapted to 55 be operated by said slide to move said rotary members into their respective grooves, and means adapted to adjust said slide.

60 In testimony whereof we have hereunto set our hands in presence of two subscribing 65 witnesses.

JOHN J. HESSE.
LUCIAN STANEK.
